Attorneys.

UNITED STATES PATENT OFFICE.

WILLIAM F. BAYER, OF BUFFALO, NEW YORK, ASSIGNOR TO THE CHASE & BAKER COMPANY,
OF BUFFALO, NEW YORK, A CORPORATION OF NEW YORK.

AUTOPIANO.

No. 926,921.

Specification of Letters Patent.

Patented July 6, 1909.

Application filed February 15, 1908. Serial No. 416,008.

To all whom it may concern:

Be it known that I, WILLIAM F. BAYER, a citizen of the United States, residing at Buffalo, in the county of Erie and State of New York, have invented a new and useful Improvement in Autopianos, of which the following is a specification.

This invention relates to pneumatic musical instruments and more particularly to so called auto-pianos adapted for either manual or automatic operation.

The object of the invention is to simplify the construction of the pneumatic action.

In the accompanying drawings: Figure 1 is a sectional front elevation of a piano embodying the invention. Figs. 2, 3 and 4 are transverse vertical sections on the correspondingly-numbered lines in Fig. 1. Fig. 5 is a transverse vertical section of the wind chest, key table and adjacent parts, on an enlarged scale. Fig. 6 is a horizontal section in line 6—6, Fig. 5. Fig. 7 is a front view of one of the abstracts and its guide-link, on an enlarged scale.

Similar letters of reference indicate corresponding parts throughout the several views.

A indicates the piano action which may be of any ordinary construction and *a* the abstracts which are manually operated by the usual piano keys *B*. The lower portions of these abstracts are guided and steadied by vertically swinging links *c*, pivoted at their rear ends to hangers or brackets *C* secured to a fixed supporting rail *C'* arranged on the rear side of the abstracts. These links preferably pass through vertical slots *d* in the abstracts and are pivoted to the latter at *d'*. The links extend forwardly beyond the abstracts to form extensions *c'*, and under these extensions engage the rear arms of vertically swinging levers *E* which are actuated by the motor pneumatic *F* of the pneumatic action of the instrument, each of the links *c* co-operating with one of the levers *E*.

The motor pneumatics are arranged in a number of rows or tiers in a manner common to such actions and are supported upon the usual wind boards or sections *g* of the wind chest *G*. The action of these motor pneumatics is controlled by the customary perforated music sheet *H* and a co-operating valve mechanism of any suitable or well known construction, one of such valve-mechanisms being shown in Fig. 5. The valve-mechanism forms no part of my present invention,

but it is preferably like that shown in Letters Patent No. 832,295, issued October 2, 1906, to The Chase & Baker Company of Buffalo, New York, as assignee of J. H. Chase and myself, to which Letters Patent reference is made for a full description of said mechanism.

In the motor pneumatics shown in the drawings, their lower boards are fixed and the usual arms *f* of their upper movable boards are connected by rods *j* with the front arms of the respective levers *E*, so that when one of such pneumatics is expanded, the front arm of the corresponding lever *E* is raised and its rear arm depressed, leaving the corresponding abstract *a* in its normal position for manual operation by the piano keys *B*. When the motor pneumatic is collapsed, the front arm of the corresponding lever is depressed and its rear arm raised, thereby raising the corresponding abstract and pneumatically operating the companion hammer of the piano action. To permit the stroke of each lever *E* to be properly regulated to obtain the desired throw of the hammer, the same is provided on its front arm with an adjustable stop or button *k* arranged to strike the base or bottom board *L* of the wind chest. Each of these stops preferably consists of a screw threaded rod or stem engaging an opening in the lever. As shown in Fig. 5, the rear end of each of these levers is preferably provided with a convex bearing face or shoe *m* to obtain a smooth action between the same and the extension *c'* of the corresponding link *c*.

The wind chest is suitably supported above the rear portions of the piano keys. In the preferred construction shown in the drawings, it rests removably upon posts *N* rising from the key table and is provided at each end with a laterally-projecting lug *o* which is clamped down upon the upper end of a post *p* by a screw *p'* entering a threaded socket in said post. The posts *p* are secured to the key table. Upon removing the screws *p'*, the wind chest is released, and after disconnecting the usual tubes or conduits leading from the main exhaust bellows to the wind chest, the latter can be removed from the piano-case.

In wind chests as ordinarily constructed, the motor pneumatics and the connections between them and the levers or other parts which actuate the abstracts are exposed or

on the outside of the wind chest. This construction is objectionable, inasmuch as the sound incident to the action of these parts is annoying and detracts from the enjoyment of the music. To overcome this objection and muffle such sounds, the wind chest is provided with a tight muffle board or plate Q which covers that side of the wind chest at which the motor pneumatics are arranged. This muffle board extends from top to bottom and from end to end of the wind chest, and in connection with the usual end and rear walls of the wind chest completely incloses the motor pneumatics, levers E and connections j, thus muffling the same. In the construction shown, the wind chest is for this purpose provided at its top, bottom and middle with horizontal cleats or boards q, q', q² which extend forwardly beyond the levers E and the arms f of the motor pneumatics and to which the muffle board Q is secured.

R indicates a vertically movable locking rail arranged above the keys B and adapted to be lowered upon the same for locking them against movement, when the instrument is played automatically, and to be raised out of the way when the instrument is to be played manually. This rail extends from end to end of the series of keys and is arranged above their rear portions, as shown. It is carried by rock arms s secured to a horizontal rock shaft s' supported on the lower rear portion of the wind chest, as best shown in Fig. 6. This shaft is actuated by one or more motor pneumatics T, the upper movable boards of which are connected by rods t with actuating arms t' secured to opposite ends of said shaft. By this construction, when the motor pneumatics T are in their expanded condition, the locking rail is supported in its elevated position as shown by full lines in the drawings, while when the pneumatics are collapsed, the rail is depressed to the dotted position shown in Fig. 5, thereby locking the piano keys. In the construction shown in the drawings, one of such motor pneumatics is arranged at each end of the wind chest, and the air ports u of each is in constant communication with the exhaust passage or conduit U leading from the usual air reservoir or exhaust device V of

the instrument to the wind chest, so that as soon as the air pumps of the instrument are operated by the customary pedals W, the motor pneumatics T are collapsed and remain in that condition as long as the instrument plays, thus automatically locking the keys the moment the instrument begins to play and automatically releasing them when it ceases playing.

I claim as my invention:

1. The combination of the abstracts of the piano-action, guide-links for the abstracts having extensions projecting forwardly beyond the abstracts, levers engaging said link-extensions, and means for operating said levers, substantially as set forth. 65

2. The combination of the abstracts of the piano-action, guide-links for the abstracts having extensions projecting forwardly beyond the abstracts, levers arranged in front of said links and engaging their extensions, and motor pneumatics for actuating said levers, substantially as set forth. 70

3. The combination of the abstracts of the piano-action, guide links for the abstracts having extensions projecting forwardly beyond the abstracts, levers arranged in front of said links and having their rear arms arranged to engage under said link-extensions, and adjustable stops carried by the front arms of said levers, substantially as set forth. 75

4. In an instrument of the character described, the combination of the key table, supporting posts rising therefrom, a wind chest removably seated on said posts, and means for clamping the wind-chest in place on said posts, substantially as set forth. 80

5. In an instrument of the character described, the combination of the key table, supporting posts rising therefrom, a wind chest removably seated on said posts, and provided with projecting lugs, fastening posts rising from the key table and supporting said lugs, and clamping screws engaging the last-named posts and bearing upon said lugs, substantially as set forth. 90

Witness my hand this 11th day of February, 1908.

WILLIAM F. BAYER.
